CANDACE WHEELER, OF NEW YORK, N. Y.

DESIGN FOR A CURTAIN FABRIC.

Design No. 17,228, dated March 29, 1887.

UNITED STATES PATENT OFFICE.

CANDACE WHEELER, OF NEW YORK, N. Y.

DESIGN FOR A CURTAIN FABRIC.

SPECIFICATION forming part of Design No. 17,228, dated March 29, 1887.

Application filed March 3, 1887. Serial No. 239,645. Term of patent 7 years.

To all whom it may concern:

Be it known that I, CANDACE WHEELER, a citizen of the United States, residing in the city, county, and State of New York, have invented and produced a new and original Design for Curtains and other Fabrics, of which the following is a specification, reference being made to the accompanying drawing, which shows a portion of a fabric containing my design.

My design consists in the conventionalized representation of the "trumpet-vine," and includes the curved stems *a*, leaves *b*, and trumpet-shaped flowers *c*, the latter being either

closed or wholly or partially opened. These parts are confused, as shown, over the whole surface to be ornamented, and interspersed among them are representations, *d*, of butterflies.

What I claim is—

The herein-described design, consisting in the representation of the stems, leaves, and flowers of the trumpet-vine and the interspersed butterflies, substantially as shown.

CANDACE WHEELER.
